UNITED STATES PATENT OFFICE.

NORMAN C. BASSETT, OF LYNN, MASSACHUSETTS, ASSIGNOR TO THE
GENERAL ELECTRIC COMPANY, OF NEW YORK.

DESIGN FOR A CASING FOR DYNAMO-ELECTRIC MACHINES OR ELECTRIC MOTORS.

SPECIFICATION forming part of Design No. 32,259, dated February 20, 1900.

Application filed January 18, 1900. Serial No. 1,944. Term of patent 14 years.

To all whom it may concern:

Be it known that I, NORMAN C. BASSETT, a citizen of the United States, residing at Lynn, County of Essex, State of Massachusetts, have invented a certain new and useful Design for a Casing for a Dynamo-Electric Machine or Electric Motor, (Case No. 1,346,) of which the following is a specification.

My present invention relates to a new and useful design for the casing of dynamo-electric machines or electric motors.

My design comprises a casing completely inclosing the operating parts, the body being substantially cylindrical in outline and provided at the sides with feet to support it and having at one end a cylindrical extension of smaller radius than the body, the ends of the casing terminating in caps above the axial line of the cylindrical extension.

The leading features of the design are the main cylindrical body of the casing and the eccentrically-arranged cylindrical extension.

Referring to the drawing by numerals, 1 represents the cylindrical body of my improved

design, and 2 2^a the feet at the sides thereof 25 to support the casing.

3 represents a cylindrical extension, the axis of which is eccentric in relation to the cylindrical body 1. The extension terminates at its end in a hollow cap 4 and the body in a 30 hollow cap 4^a, which form seats for the armature-shaft. The extension is provided with openings 5 5^a, circumferentially arranged in the same cross-sectional plane, and the body with a larger opening covered by a curved 35 plate 6 to permit insertion and withdrawal of the armature.

I claim—

The design for a casing for a dynamo-electric machine or electric motor substantially 40 as shown and described.

In witness whereof I have hereunto set my hand this 16th day of January, 1900.

NORMAN C. BASSETT.
